JIG AND METHOD FOR RECONDITIONING
THE ALIGNING EDGES OF LUGS OF MAT-
RICES AS USED IN TYPESETTING MA-
CHINESRobert J. Lloyd, Detroit, Mich.; Arthur Philp, ex-
ecutor of said Robert J. Lloyd, deceased

Application August 31, 1938, Serial No. 227,845

9 Claims. (Cl. 29—1)

The present invention relates to jigs, and particularly to a jig for reconditioning the damaged lugs of matrices as used in typesetting machines.

Matrices are provided at one end with projecting lugs, one on the casting face side, known as the casting face lug, and one on the reading face side known as the reading face lug. On the casting face side of the matrix, the top edge of the lug is the aligning edge for the matrix, the bottom edge performing no function in the aligning operation. On the reading face side of the matrix, the bottom edge of the lug is the aligning point for the matrix, the top edge performing no function in the aligning operation. These aligning edges of the lugs of matrices become damaged, caused by an operator of a typesetting machine forcing down what is known as a tight line, or to faulty adjustment of one of the elevators in the machine. When the lugs become damaged, the matrices are of no further use, for the reason that the damaged lugs cause the indicia on the matrices to be cast offset and out of alignment in the cast line, and consequently certain letters or numerals would be offset in a printed line.

It is therefore an object of the present invention to provide a jig with means, whereby the damaged aligning edges of the lugs of matrices may be reconditioned and restored to their original condition.

Another object of the present invention is the provision of a jig adapted for use, either by a right handed or left handed operator in the reconditioning operation.

A still further object of the present invention is the provision of a jig, portions of which may be used as an anvil to straighten and flatten the lugs if they become bent or burred during the reconditioning operation.

A still further object of the present invention is the provision of a jig equipped with tool receiving means, i. e., parts of the jig to be used as a filing gauge to restore lugs, after being reconditioned, to the exact size of the original matrix, both in width and height of the aligning lugs.

A still further object of the present invention is the provision of means for holding matrices in the jig during the reconditioning operation.

A still further object of the present invention is the provision of a jig, means in the jig for receiving matrices, and means for realigning the lugs of matrices.

A still further object of the present invention is the provision of a gauge means for recondi-

tioned matrices, to determine the width, height of and distance between aligning lugs of repaired matrices.

A still further object of the present invention is the provision of a jig provided with means for receiving matrices of all sizes.

Other objects of the present invention will be more fully understood from the following description and claims when the same are read in connection with the drawings accompanying and forming part of this specification in which:

Figure 1 is a perspective view of my novel jig, and illustrating matrix receiving means for the reconditioning of the aligning edge of the casting face lug.

Figure 2 is a perspective view of the reverse side face of my novel jig and illustrating the matrix receiving means for the reconditioning of the aligning edge of the reading face lug.

Figure 3 is an end elevational view of the right hand end of the jig illustrated in Figure 1.

Figure 4 is an end elevational view of the left hand end of the jig illustrated in Figure 2.

Figure 5 is a perspective view of a swedge tool used for upsetting the reading face lug of a matrix in the jig.

Figure 6 is a perspective view of a spring clamp for holding a matrix in the jig during the reconditioning operation.

Figure 7 is a gauge for testing a reconditioned matrix for width of the lugs, distance between the inner edges of the top and bottom lugs and the length of the matrix.

Figure 8 is an elevational view of the casting face side of the jig and illustrating a matrix positioned therein with the casting face lug damaged, a portion of the jig being held in a vise, the vise and hammer shown fragmentarily.

Figure 9 is a view similar to Figure 8, the matrix being reversed in the jig and illustrating the reconditioned aligning edge of the casting face lug, the aligning edge being uniplanar with one wall of the transverse slot.

Figure 10 is an elevational view of the casting face of the jig and illustrating an extra thick matrix in the jig, the damaged aligning edge of the casting face lug being shown, and a hammer in position illustrating the operation of reconditioning the lug, a portion of the jig held in a vise, the vise and a portion of the hammer being shown fragmentarily.

Figure 11 is an elevational view of the jig, the casting face being forward and illustrating a matrix in dotted lines positioned in the opposite or reading face portion of the jig for recondi-

tioning the aligning edge of the matrix by a right handed operator, a portion of the jig held in a vise, the vise shown fragmentarily.

Figure 12 is an elevational view of the reading face of the jig and illustrating a matrix in position for reconditioning the aligning edge of the matrix by a left handed operator, a portion of the jig being held in a vise and shown fragmentarily.

10 Figure 13 is a view similar to Figure 11 and illustrates an assembly of jig, matrix, clamp and swedge tool, for reconditioning the aligning edge of the reading face lug of the matrix.

15 Figure 14 is a sectional view taken on line 14—14 of Figure 13 looking in the direction of the arrows, the swedge tool (not shown).

Figure 15 is an elevational view of a new matrix and illustrates the shape of the lugs.

20 Figure 16 is an elevational view of the damaged lugs of a matrix.

Figure 17 is an elevational view of a matrix, the aligning edge of the casting face lug having been reconditioned.

25 Figure 18 is an elevational view of a matrix, the aligning edge of the reading face lug having been reconditioned.

Figure 19 is an elevational view of a matrix and illustrating the shape of the aligning edges of the lugs after they have been reconditioned.

30 Figure 20 is an end elevational view of the left hand end of the jig as illustrated in Figure 10 and illustrates the position of an extra thick matrix in the jig, the hammer and vise being omitted.

35 Referring to the drawings, the numeral 21 represents my novel jig of any suitable material and by preference case hardened steel, having a face A, a face B and walls D, E, F, and G. The face A of the jig has a longitudinal rabbeted portion 22, a stud or block portion 23 and studs 24 and 25, the stud 24 being of substantially oblong configuration and having its end wall 26 spaced from the end wall 27 of the stud or block 23, the opposite end wall 28 of the stud 24 having a cut out 40 portion of substantially L-shaped configuration for a purpose to be later described. The stud 25 is of a smaller oblong configuration than the stud 24 and has one end wall 29 spaced from the wall 27 of the block or stud 23, and it is to be further noted that the end wall 29 is not uniplanar with the end wall 26. From the wall 27 of block 23 to wall F the length is of a predetermined one. The inner wall 30 of stud 25 is spaced from the inner wall 31 of the stud 24 a 45 predetermined distance, the walls forming a channel way or slot 32. A transverse slot or channel way 33 is formed in the face A as illustrated in Figure 1 of the drawings, the slot or channel way being in communication with the slot or 50 channel way 32, the channels or slots forming a T-shape configuration, the slot or channel way 32 being marked with the letter C indicating the casting face of the jig. The top faces of the stud or block 23 and studs 24 and 25 are in the 55 same flat plane. The longitudinal wall 34 of block 23 and the longitudinal wall 35 of stud 24 are uniplanar.

As illustrated in Figure 1 of the drawings, the wall E of the jig has a transverse cut out portion 50 36 that forms a slot 37 having an inclined or beveled wall 38, a portion of the wall E serving as an anvil.

The wall F has a cut out portion 39, a portion 55 40 of which is of L-shape configuration, and it 75 is continuous with the L-shape configuration in

the wall 28 of the stud 24, the remaining portion in the cut 39 having an inclined wall 41.

The face B of the jig has a longitudinal rabbeted portion 42 similar to the rabbeted portion 22 in the face A and it is to be noted the rabbeted portion 42 is diagonally opposite to the rabbeted portion 22. The face B is also provided with a stud or block 43, and studs 44 and 45, the stud 44 being of oblong configuration and having its end wall 46 spaced from the end wall 47 of the stud or block 43 a predetermined distance, the opposite end wall 48 being offset from the wall D a predetermined distance. The stud 45 is of a smaller oblong configuration than the stud 44 and has one end 49 spaced from the wall 47 of the block or stud 43, the opposite end wall 50 being offset from wall D. The walls 46 and 49 are uniplanar, and these walls and wall 47 form a transverse slot 51 for a purpose to be later described. The end walls 48 and 50 are also uniplanar. The inner wall 52 of stud 45 is spaced from the inner wall 53 of stud 44 a predetermined distance and these walls form a channel way or slot 54, the channel way or slot 54 being in communication with the transverse slot 51, the channels forming a T-shaped configuration. The top faces of the stud or block 43 and studs 44 and 45 are in the same flat plane.

As illustrated in Figure 2 of the drawings, wall G has a transverse slot 55 that is in communication with the channel or slot 32, the wall portion 56 serving as an anvil.

In Figure 15 I have illustrated a new matrix showing the configuration of the casting face lug 58 and the reading face lug 59, and in Figure 16 35 I have illustrated the matrix 57 showing the sheared or damaged aligning edge 60 of the casting face lug and the sheared aligning edge 61 of the reading face lug.

In the use of my novel jig, to recondition the 40 aligning edge of the casting face lug of the matrix, the jig is locked in a vise 62, the face A of the jig facing the operator. The matrix 57 is positioned in the jig as illustrated in Figure 8 of the drawings, the matrix 57 being held in the jig by the 45 thumb and fingers (not shown) of the left hand of the operator or by the clamp 63 illustrated in Figure 6 and in the assembly in Figure 13. From Figure 8 of the drawings, it can be seen, that the matrix 57 fits snugly into the channel or slot 32, the ends 64 and 65 of the matrix impinging against the wall 27 of the block or lug 23, a portion of the aligning edge 60 of the casting face lug impinging the end wall or lip 66 of the stud 25 and the top edge 67 of the reading face lug impinging the end wall or lip 68 of the stud 24. The bottom edge 69 of the casting face lug is hammered by the hammer 70, held in the right hand of the operator, and as illustrated in Figure 8, the hammer is held at an angle to the lug, the lug 60 being hammered until the aligning edge 60 is at right angles to the longitudinal casting face edge 71 of the matrix. When the aligning edge is at right angles to the casting face edge, the matrix is reversed in the jig as illustrated in Figure 9 65 of the drawings. If the aligning edge 60 of the matrix is not uniplanar with the wall 72 of the transverse slot 55 a file (not shown) is inserted into the slot and the edge of the matrix filed until it is uniplanar with the wall 72, the file 70 is also run over the side wall G of the jig to make the side edge 73 of the lug uniplanar with the side wall G.

Where the casting face lug of an extra heavy or thick matrix has to be reconditioned, I have 75

provided a means for the operation in the wall F of the jig as illustrated in Figures 10 and 20. The matrix is positioned in the casting face slot 32 of the jig and the jig then clamped in the vise 62 as illustrated in Figure 10, the beveled portion 41 and the cut out portion 38 permits the hammer to be used to hammer the aligning edge of the lug in the same manner as described for the operation in Figure 8, except, that instead of the aligning edge of the casting face lug being hammered to the lip 66 it is hammered to the lip 68 of the stud 24 until it is flush with the lip 68, and at right angles to the longitudinal casting face edge of the matrix. The jig is then released from the vise and positioned as shown in Figure 9, the matrix being positioned in the casting face slot of the jig as shown in Figure 9, and if the aligning edge of the matrix is not uniplanar with the adjacent wall 72 of the transverse slot 55, the edge is filed until it is uniplanar with the wall, the file is also run over the side wall G of the jig to make the side edge of the lug uniplanar with the side wall. The jig as illustrated in Figures 8 and 10 is adapted for a left or right handed operator.

In the reconditioning of the aligning edge of the reading face lug by a right handed person, the jig is positioned in the vise as illustrated in Figure 11, the casting face A of the jig facing the operator, the matrix being positioned in the reading face slot 54 and held therein by the clamp 63 as illustrated in Figure 13 of the drawings. The swedge tool 73 having a rounded nose portion 74 is held in the position as indicated in the assembly Figure 13 and the end 75 of the tool hammered with the hammer 70 until the aligning edge 61 of the reading face lug is flush or parallel with the wall 47 of the stud or block 43 and uniplanar with the bottom edge 76 of the matrix. The matrix is then reversed in the slot 54, with the reading face lug up and a file run over the wall E, the side edge of the reading face lug being made uniplanar with the wall E and the file run over wall D to make the bottom edge of the matrix uniplanar with the wall D.

In the reconditioning of the aligning edge 61 of the reading face lug 59 by a left handed operator, the jig 21 is secured in the vise 62 with the reading face B facing the operator as illustrated in Figure 12. The matrix 57 is held in the slot 54 by the spring 63 as illustrated in the assembly, Figure 13. The swedge tool 73 is held in the right hand and the end 75 hammered with the hammer 70 until the aligning edge 61 of the reading face lug is flush or parallel with the wall 47 of the stud or block 43 and uniplanar with the bottom edge 74 of the matrix. The operation for filing the side edge of the lug and the bottom edge of the matrix is the same as for a right handed operator.

After the aligning edges of the casting face and reading face lugs of the matrix have been reconditioned, the matrix is then ready to be tested for size, and for the sizing tests I have provided a gauge 77 illustrated in Figure 7, the gauge being provided with two openings and a shoulder. The opening 78 stamped on the gauge with the numeral 1 is for measuring from the top to bottom on the reading edge side of the matrix, the bottom edge 61 of the lug being the aligning edge of the lug, and this side of the matrix must fit tight in the opening 78. After testing the reading face side, the shoulder 79 stamped with the numeral 2 on the gauge is applied to the casting face side of the matrix to test for distance

between the bottom edge 80 of the top lug and the aligning edge 60 of the casting face lug, and the shoulder must fit tight between the lugs. The opening 81 stamped on the gauge by the numeral 3, is for measuring the bottom width of the matrix, the side edges of the casting face lug and the reading face lug must be uniplanar with the top companion lugs of the matrix, the bottom width of the matrix being identical with the top width, the transverse bottom portion of the matrix must fit tight in the opening 81.

Changes in detail may be made without departing from the scope of the claims hereto appended.

What I claim is:

1. The method of reconditioning the aligning edges of lugs of matrices which consists in placing the casting face of a matrix in a channel in one face of a jig, locking the jig in a vise, hammering one edge of the casting face lug until the opposite or aligning edge of said lug is at right angles to the casting face edge of the matrix, reversing the matrix in the channel and truing the aligning edge. 15

2. The method of reconditioning the aligning edges of lugs of matrices which consists in placing the casting face of a matrix in a channel in one face of a jig, locking the matrix in the channel with a clamp, locking the jig in a vise, hammering one edge of the casting face lug until the opposite or aligning edge of said lug is at right angles to the casting face edge of the matrix, reversing the matrix in the channel and truing the aligning edge. 20

3. The method of reconditioning the aligning edges of lugs of matrices which consists in placing the reading face of a matrix in a channel in one face of a jig, locking the jig in a vise, clamping the matrix in the channel, contacting one end of a swedge tool with one edge of the reading face lug, hammering the swedge tool until the aligning edge of said lug is at right angles to the reading face edge of the matrix and uniplanar with the bottom edge of the matrix, removing the matrix from the jig and testing the matrix with a gauge for width and height. 35

4. A jig for reconditioning matrices for typesetting machines comprising a body, the opposite faces of which are provided with vise engaging rabbeted portions, said faces further provided with studs of different sizes, certain of the walls of said studs forming channel means in said faces for matrices, the ends of some of the studs being uniplanar with a wall of the body. 50

5. A jig for reconditioning matrices for typesetting machines comprising a body, the opposite faces of which are provided with vise engaging rabbeted portions, said faces further provided with studs of different sizes, certain of the walls of said studs forming channel means in said faces for matrices, the ends of some of the studs being uniplanar with a wall of the body, one end of one of said studs being of L-shape configuration. 55

6. A jig for reconditioning matrices for typesetting machines comprising a body, the opposite faces of which are provided with vise engaging rabbeted portions, said faces further provided with studs of different sizes, certain of the walls of said studs forming channel means in said faces for matrices, the ends of some of the studs being offset from a wall of the body. 60

7. A jig for reconditioning matrices for typesetting machines comprising a body, the opposite

faces of which are provided with vise engaging rabbeted portions, said faces further provided with studs of different sizes, certain of the walls of said studs forming channel means in said faces, and certain of the walls of said studs adapted for aligning, aligning edges of matrices.

8. A jig for reconditioning matrices for type-setting machines comprising a body, the opposite faces of which are provided with vise engaging rabbeted portions, said faces further provided with studs of different sizes, certain of the walls of said studs forming channel means in said faces, certain of the side walls having transverse channel means and a beveled portion, and cer-

tain of the walls of said studs adapted for aligning, aligning edges of matrices.

9. A jig for reconditioning matrices for type-setting machines comprising a body, the opposite faces of which are provided with vise engaging rabbeted portions, said faces further provided with studs of different sizes, certain of the walls of said studs forming channel means in said faces, certain of the side walls having transverse channel means and a beveled portion, certain of the walls of said studs adapted for aligning, aligning edges of matrices, the top faces of said studs on each face of the body being uniplanar.

ROBERT J. LLOYD.
